TIME INSTRUMENT

Stanley Marsh Kenerson, Springfield, Mass., assignor to The Standard Electric Time Company, Springfield, Mass., a corporation

Application January 7, 1935, Serial No. 689

4 Claims. (Cl. 58—125)

This invention relates to improvements in time instruments, and more particularly to speed-reduction gearing, primarily for use in time instruments.

5 One object of this invention is to provide an improved speed-reduction gearing formed of simple elements readily manufactured and readily assembled, to produce an efficient, quiet construction.

10 With the above and other objects in view, this invention includes all improvements over the prior art which are disclosed in this application.

In the accompanying drawings, in which one way of carrying out the invention is shown for 15 illustrative purposes:

Fig. 1 is a rear elevation of an impulse-clock movement made in accordance with this invention;

Fig. 2 is a sectional view on line 2—2 of Fig. 1; 20 Fig. 3 is a sectional view on line 3—3 of Fig. 2, illustrating an improved speed-reduction gearing made in accordance with this invention;

Fig. 4 is an enlarged view of the central portion of Fig. 3;

25 Fig. 5 is a view similar to Fig. 4 of the speed-reduction gearing, with parts of the latter in different cooperative position; and

Fig. 6 is a sectional view on line 6—6 of Fig. 5.

In the description and claims, the various parts 30 are identified by specific names for convenience, but they are intended to be as generic in their application as the prior art will permit.

In the particular construction herein disclosed and which is more fully described in my co-pending application, Serial No. 690, filed January 7, 1935, front and rear movement-plates 10 and 11 are secured together in spaced relation by four pillars 12. The front movement-plate 10 has a recess 13 and a wall-portion 14, having an aperture 15 in which is rotatably mounted a time- or hour-sleeve 16. A time- or minute-arbor or shaft 18 is rotatably supported in the hour-sleeve 16 and in an aperture 17 in the rear movement-plate 11. The minute-shaft or arbor 18 is given 40 a step-by-step rotational movement by the ratchet-wheel construction 18a actuated by the pawls 19 and 20, which are pivotally connected to the arm 21 which, in turn, is fixedly secured on the pawl-shaft 22, the pawl-shaft 22 being given

45 an oscillating movement by means of the armature 23, oscillated in one direction by the poles 24 and 25 of the electromagnet 26, and oscillated in the opposite direction by the spring 27 acting upon one end of the limit-bar 28.

50 The speed-reduction gearing or dial-work in-

cludes a large or outer gear 29 fixedly secured to the hour-sleeve 16 and has a recess 30 and inwardly-directed or internal gear-teeth 31, the number of which, in the form of the invention illustrated, is twelve. A ring-gear 32 has eleven 5 outwardly-directed teeth 33, adapted to mesh with the teeth 31 of the outer gear.

A central, cylindrical opening 34 in the ring-gear 32 is rotatably engaged by the cylindrical surface 35 of the eccentric 36, which latter is 10 fixedly secured on the reduced portion 37 of the minute-shaft 18 and against the shoulder 38 formed by the enlarged portion 39 of the minute-shaft 18. The annular flange 40 of the eccentric engages against the ring-gear 32 and holds it in 15 position in the recess 30 in the outer gear.

A feather or spline-like member 41 is secured by screws 42 to the ring-gear 32, and has a finger or spline-portion 43 which slidably engages in a slot 44 in the portion 45 of the front movement-plate 10 bordering the recess 13. The minute-arbor or shaft 18 may have secured thereto a minute-hand 46 and the hour-sleeve 16 may have an hour-hand 47 secured thereto and which, of course, will rotate at one-twelfth the speed of 25 the minute-hand 46. This will be accomplished by the construction illustrated in the drawings, inasmuch as the relation of the two gears is as of eleven teeth to twelve, and when the time-shaft or minute-shaft 18 makes one revolution, 30 and moves from its lowermost position shown in Fig. 4, the eccentric 36 will cause the ring-gear 32 to move to the right and up to its topmost position shown in Fig. 5, and then move to the left and down to its original position shown in 35 Fig. 4, in the meantime causing successive engagement of the teeth of the two gears in a manner that will be readily appreciated, and thus advancing the large outer gear a distance of one tooth or one-twelfth of a revolution, thus giving 40 the hour- or time-sleeve 16 a rotational speed one-twelfth that of the time- or minute-arbor 18. The finger or spline-portion 43 by slidably engaging in the slot 44, permits the ring-gear to be moved bodily by the eccentric, but prevents 45 the ring-gear from having a true rotary motion inasmuch as the lower portion of the ring-gear has substantially only an up-and-down sliding action.

The invention may be carried out in other 50 specific ways than that herein set forth without departing from the spirit and essential characteristics of the invention, and the present embodiment is therefore to be considered in all respects as illustrative and not restrictive, and all 55

changes coming within the meaning and equivalency range of the appended claims are intended to be embraced therein.

I claim:

- 5 1. A time instrument construction including: a supporting-structure provided with a slot; a time-sleeve rotatably supported by said supporting-structure; a time-shaft concentric with and rotatable relatively to said time-sleeve; an outer gear fixedly secured to said time-sleeve and having internal gear-teeth; an eccentric fixedly secured to said time-shaft; a ring-gear 10 rotatably mounted on said eccentric and having gear-teeth around its periphery of lesser number than the number of gear-teeth of said outer gear and adapted to mesh with the teeth of said outer gear; and a finger secured to said ring-gear and slidably engaging in said slot of said supporting-structure and adapted to permit the ring-gear 15 to be moved bodily by said eccentric but to prevent the ring-gear from rotating.
15 2. A time instrument construction including: a supporting-structure including a wall provided with a recess, and a slot intersecting said recess; a time-sleeve rotatably supported by the recessed portion of said wall; a time-shaft concentric with and rotatable relatively to said time-sleeve; an outer gear in said recess and fixedly secured to said time-sleeve and having a gear recess and internal gear-teeth; an eccentric fixedly secured to said time-shaft; a ring-gear 20 in said gear-recess and rotatably mounted on said eccentric and having gear-teeth around its periphery of lesser number than the number of gear-teeth of said outer gear and adapted to mesh with the teeth of said outer gear; said eccentric having a flange holding said ring-gear in said gear-recess; and a finger secured to said ring-gear and slidably engaging in said slot of said 25 wall and adapted to permit the ring-gear to be
- 20 3. A time instrument construction including: a supporting-structure including a wall having a recess; a time-sleeve rotatably supported by the recessed portion of said wall; a time-shaft concentric with and rotatable relatively to said time-sleeve; an outer gear in said wall recess and fixedly secured to said time-sleeve and having a gear-recess and internal gear-teeth; an eccentric fixedly secured to said time-shaft; a ring-gear 25 in said gear-recess and rotatably mounted on said eccentric and having gear-teeth around its periphery of lesser number than the number of gear-teeth of said outer gear and adapted to mesh with the teeth of said outer gear; and means interconnecting said ring-gear and said supporting-structure and adapted to permit the ring-gear to be moved bodily by said eccentric but to prevent the ring-gear from rotating.
25 4. A time instrument construction including: a supporting-structure including a wall having a recess; a time-sleeve rotatably supported by the recessed portion of said wall; a time-shaft concentric with and rotatable relatively to said time-sleeve; an outer gear in said wall recess and fixedly secured to said time-sleeve and having a gear-recess and internal gear-teeth; an eccentric fixedly secured to said time-shaft; a ring-gear 30 in said gear-recess and rotatably mounted on said eccentric and having gear-teeth around its periphery of lesser number than the number of gear-teeth of said outer gear and adapted to mesh with the teeth of said outer gear, said eccentric having a flange holding said ring-gear in said gear-recess; and means secured to said ring-gear and slidably engaging said supporting-structure and adapted to permit the ring-gear to be moved bodily by said eccentric but to prevent the ring-gear from rotating.
